[57] CLAIM

The ornamental design for a nested table, as shown and described.

DESCRIPTION

FIG. 1 is a front elevation view of a nested table, showing my new design, the right side, left side and rear elevation being identical thereto;

FIG. 2 is a top plan view thereof;

FIG. 3 is a bottom plan view thereof;

FIG. 4 is a perspective view showing an inner table removed from the nested table design;

FIG. 5 is a perspective view showing both the inner and intermediate tables removed from the nested table design;

FIG. 6 is a front elevation of a fixed nested table showing an alternative embodiment of my new design, the right side, left side, and rear elevation being identical thereto;

FIG. 7 is a top plan view thereof; and,

FIG. 8 is a bottom plan view thereof.
